UNITED STATES PATENT OFFICE.

JAMES ANDERSON, OF CHICAGO, ILLINOIS.

IMPROVEMENT IN SLIDE AND STEAM VALVES.

Specification forming part of Letters Patent No. **158,229**, dated December 29, 1874; application filed October 24, 1874.

To all whom it may concern:

Be it known that I, JAMES ANDERSON, of Chicago, in the county of Cook and State of Illinois, have invented a new and valuable Improvement in Steam-Valves; and I do hereby declare that the following is a full, clear, and exact description of the construction and operation of the same, reference being had to the annexed drawings making a part of this specification, and to the letters and figures of reference marked thereon.

Figure 1 of the drawing is a representation of a sectional view of my steam-valve, and Fig. 2 is a plan view of the same.

This invention has relation to means for relieving slide-valves from undue friction, by exposing their backs to the atmosphere; and it consists in combining an adjustable hollow trunk, provided with flanges, and resting on top of the slide-valve, and adjustable cap, having a central opening and flange, with an elastic ring between the hollow trunk and cap, as will be hereinafter more fully set forth.

In the annexed drawings, A designates a slide-valve of the **D** kind, which is constructed with a long table, *a*, forming the back of the valve. Through the top of the valve-chest B a hole is made, which is preferably of circular form, and which receives through it a trunk, C, the lower end of which is flanged, as shown at *b*, and ground so as to form a steam-tight joint on the back surface of the valve. D designates a flanged gland, which surrounds the trunk C, and which serves, in combination with a packing, *c*, and nuts *d* on posts *e*, to make a steam-tight joint around said trunk.

E designates a circular cap, having a hole, *g*, through it, and an annular flange or rib, *f*, on its lower side. This cap E is confined down upon the trunk C by means of nuts *h* *h'*, applied on the screw-posts *e*. The nuts *h'*, underneath the cap E, serve as jam-nuts. Between the cap E and trunk C a ring of india-rubber, or other suitable elastic substance, is applied, as shown at *i*, Fig. 1, the object of which is to allow the trunk C to be held down on the back of the valve A with a slight elastic pressure.

It will be seen from the above description that nearly the entire back of the valve is exposed to the atmosphere by means of the hollow trunk C and perforated holding-down cap E; also, that the trunk C can be held down on the back of the valve with any desired degree of pressure, and adjusted as circumstances require.

What I claim as new, and desire to secure by Letters Patent, is—

The hollow trunk C, provided with flanges *b* *b'*, and resting on top of the slide-valve A, in combination with the adjustable cap E, provided with a central opening, *g*, and flange *f*, the elastic ring *i*, and adjustable gland D, substantially as described, and for the purpose set forth.

In testimony that I claim the above I have hereunto subscribed my name in the presence of two witnesses.

JAMES ANDERSON.
